We claim the ornamental design for a toy vehicle track link, as shown and described.

DESCRIPTION

FIG. 1 is a top perspective view of the toy vehicle track link;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken or dashed lines included in the figures depict portions of the article that form no part of the claim. The shading illustrated in the figures is provided merely to represent the contour of the design and is not intended to be illustrative of the texture, gloss, or surface decoration.
